UNITED STATES PATENT OFFICE.

SEYMOUR GEORGE, OF PITTSBURG, PENNSYLVANIA, ASSIGNOR OF ONE-HALF TO CHARLES FRANCIS HARRIS, OF PITTSBURG, PENNSYLVANIA.

JET PROPULSION APPARATUS FOR VESSELS.

SPECIFICATION forming part of Letters Patent No. 750,533, dated January 26, 1904.

Application filed September 2, 1898. Renewed October 30, 1903. Serial No. 179,238. (No model.)

To all whom it may concern:

Be it known that I, SEYMOUR GEORGE, a citizen of the United States, residing at Pittsburg, Allegheny county, State of Pennsylvania, have 5 invented certain new and useful Improvements in Jet-Propulsion Apparatus for Vessels; and I do hereby declare the following to be a full, clear, and exact description of the invention, such as will enable others skilled in the art to 10 which it appertains to make and use the same.

My invention relates to improvements in means for propelling vessels, and in particular to improvements in the propulsion of vessels by means of jets.

15 The fundamental principle of jet propulsion for vessels consists in forcing a stream of water or other fluid outward from the vessel, which stream reacts upon the body of water in which the vessel floats, and thereby tends to cause 20 such vessel to move in a direction opposite to that in which the jet is projected.

Hitherto jet propulsion has been considered less efficient than propulsion by the screw-propeller, owing to disadvantages inherent in the 25 apparatus employed. In jet propulsion it is absolutely necessary for practical purposes that the jet be of considerable size and velocity. This, therefore, necessitates the employment of apparatus of great power in order to project 30 a sufficient body of water to propel the vessel at a suitable speed. Such apparatus comprises pumps for pumping the water, engines for driving the pumps, and means for delivering the water in a stream or jet outside the 35 vessel. If reciprocating engines and pumps are employed for such a purpose, it is found that the change in direction of stroke of the reciprocating parts gives rise to such serious vibrations that it is practically impossible to 40 run such apparatus at a quick speed, and since speed is one of the functions of the power a limitation in speed requires an increase in the capacity of the pump-cylinders and engine-cylinders and a consequent increase in bulk of 45 the whole apparatus until the point is finally reached when it is found that the weight and bulk of such reciprocating engines and pumps for the practical jet propulsion of a vessel are so excessive in comparison with the tonnage 50 of the vessel as to prohibit their successful

use. While these defects are somewhat avoided by the use of reciprocating engines and rotary pumps, still the disadvantages due to the employment of such engines are great enough to render the whole apparatus a failure, especially because the ordinary rotary pumps are wasteful unless run at high speeds such as cannot well be furnished by such heavy engines. 55

For the above reasons it has been recognized 60 that theoretically a rotary motor should be preferable to a reciprocating engine for the purpose of driving the rotary pumps; but in practice it has been found that the rotary motors hitherto employed have been open to 65 many disadvantages, which render it practically impossible to run them at high speed, some of these disadvantages being even more serious than those of the reciprocating engines. For instance, in those rotary motors 70 hitherto constructed the wear on the rotating piston parts has been excessive, and particularly at high speeds, such wear reaching an undesirable stage after a very short operation of the motor. Such rapid wear of the piston 75 parts renders the motor wasteful of steam, and therefore expensive in comparison with reciprocating engines. The efforts of inventors in the improvement of such rotary motors hitherto seems to have been directed 80 principally toward providing means for taking up such wear on the piston parts, whereby the motor may be run for a longer time without renewing the piston parts. These efforts have not been entirely successful and, 85 indeed, may be said to have been practically unsuccessful so far as large quick-running motors are concerned. On the other hand, my invention may be said to be distinguished 90 from such previous efforts in that it tends more particularly toward the prevention of such wear rather than toward compensating for the wear after it has occurred. Of course some wear will take place in the piston parts even under my invention; but this is so slight 95 that a very simple means will allow me to compensate for the same, which means will require attention only at long intervals.

In addition to the disadvantages inherent in previous motors, as above pointed out, I 100

have discovered that some of the serious disadvantages which have caused the failure of jet-propulsion apparatus have been due to the manner of coupling the rotary motors and rotary pumps—that is to say, the most efficient rotary pumps are those having two coordinate rotary pistons intermeshing with each other, these pistons each being mounted on a shaft, which shafts are geared together. If now a rotary motor or motors be employed to rotate a single shaft and this shaft be connected to one of the shafts of the rotary pump, as has been previously done, the second piston and shaft of the pump are rotated through the gearing which transfers the power from one shaft of the pump to the other. In this arrangement great lateral pressure is brought to bear upon the single shaft of the motor and upon both shafts of the pump, thus soon wearing their bearings, so that they finally spread apart, and this action, even though but very slight, throws a lateral strain on the motor and pump pistons, thus causing them to wear unduly and to generate an excessive amount of friction. For these reasons also it has been found impossible in practice to operate powerful rotary pumps and motors at a sufficiently high speed to make jet propulsion a success.

Another equally important defect of previously-constructed jet-propulsion apparatus has been in what I may term the "jet apparatus proper"—that is to say, the inlet and discharge pipes by which the water is supplied to the pumps and then forced outward into the body of water in which the vessel floats. In such previous constructions all the jet apparatus proper was below the normal water-line of the vessel, and as a consequence variations in the amount of water outside the vessel above or below such a normal water-line, such as would be caused by heavy seas in stormy weather, would cause a variation in the load on the pumps and motors from a maximum to a minimum, the minimum load causing a sudden racing of the motors and pumps, while the maximum load would tend to bring the machinery to a dead stop. Since these variations would take place in stormy weather with rapid alternations, it was impossible to satisfactorily govern the motors at ordinary speeds, and hence the use of the motors at high speeds was entirely out of the question, and, as a final result, unless the motors could be run at high speed they were so wasteful of steam as to be more disadvantageous than ordinary reciprocating engines. Furthermore, a high-speed rotary engine or motor if suddenly relieved of its load was exposed to greater danger of breakage than a reciprocating engine, since the increase of the centrifugal force in its heavy rotating pistons would tend to burst them or at any rate cause a swelling due to the elasticity of the material, which would cause the pistons to grind against the insides of the cylinders, thereby causing

a wear which upon the reduction of the speed to the normal rate of the motor would result in a leakage of steam around the worn edges of the piston, it being impossible to stop the machinery at frequent intervals and take up such wear in view of the danger to the vessel in stormy weather.

It is the object of my invention to overcome all these disadvantages, as above pointed out.

With this object in view and some others, which will be obvious to those skilled in the art from the description hereinafter, an apparatus embodying my invention, broadly considered, consists in a specially-constructed motor so coupled to a particularly-selected and somewhat-modified form of rotary pump that the disadvantages hitherto due to the joint operation of rotary pumps and motors will be avoided, the whole being combined with a new form of jet apparatus, whereby the latter maintains a uniform load on the pump, which therefore enables the motor to be run at a maximum high speed with the assurance that diminutions in the pressure of water outside the vessel will not cause the racing of the motor at a speed above its maximum.

My invention consists, further, in certain specified features of construction, details, and combinations of parts, which will first be described in connection with the accompanying drawings and then particularly pointed out in the claims.

In the drawings, Figure 1 is a plan view of the invention in its entirety; Fig. 2, a substantially central vertical longitudinal section through the siphon, the discharge-valves and pipes, and the junction-pipe and valve, the siphon being rotated ninety degrees to bring it into the vertical plane of the other parts; Fig. 3, a similar view with the parts in their reversed position, the siphon being removed; Fig. 4, a vertical cross-section on the line 4 4 of Fig. 2; Fig. 5, a vertical cross-section on the line 5 5 of Fig. 2; Fig. 6, an enlarged detail view, partly in plan and partly in section, of the reversing-valve with its shaft and gear; Fig. 7, a vertical cross-section through the hull of a vessel and through a pair of discharge-valves; Fig. 8, a bottom plan of the parts seen in Figs. 2 and 3; Fig. 9, a vertical cross-section through one of the rotary steam-motors on the line 9 9, Fig. 11; Fig. 10, a similar view on the line 10 10, Fig. 11; Fig. 11, a view in plan view, showing four rotary piston-motors compounded; Fig. 11^a, an enlarged sectional detail of one of the adjustable piston-heads of the motor seen in Figs. 9 and 10; Fig. 11^b, a vertical section on the line 11 11 of Fig. 11^a; Fig. 12, a vertical cross-section through the hull of a vessel and taken centrally through the feed-pipes, their valves, the reversing-valve, siphon, and air-valve, the siphon being rotated ninety degrees to bring it into the same vertical plane with the other parts; Fig. 13, a cross-section of one of the pumps; Fig. 13^a

- 14, a view similar to Fig. 11, but showing a different arrangement of the motors whereby the power is all upon one shaft; Fig. 15, a vertical cross-section on the line 15 15 of Fig. 14; 5 Fig. 16, a plan view showing the manner of compounding the pumps; Fig. 17, a detail of the adjustable gear; Fig. 18, a section on the line 18 18 of Fig. 17; Fig. 18^a, a detail view of one of the locking-plugs; Fig. 19, a detail 10 plan view, partly in section, showing the roller-boxing and the stuffing-boxes; Fig. 20, an enlarged end elevation of the gears of the shafts of the boxing; Fig. 21, an end elevation of portions of the stuffing-box; Fig. 22, an enlarged 15 sectional view of the boxing; Fig. 23, an end view thereof with parts in section; Fig. 24, an enlarged central longitudinal section showing the construction of the stuffing-box; Fig. 25, an elevation showing the gearing for operating simultaneously the screws for adjusting the roller-bearing; Fig. 26, a top plan view of the motor-base; Fig. 27, an elevation of the same; Fig. 28, a detail in elevation of the male portion of the coupling; Fig. 29, an end view thereof; Fig. 30, a similar 20 view of the female portion; Fig. 31, a central section, and Fig. 32 an elevation of the steam throttle-valve employed by me.

For convenience I will describe my invention under the following heads:

- 30 A. The jet device, which comprises the following: first, the feed mechanism for supplying the pumps with water and suitably controlling such supply; second, the discharge mechanism for transmitting the water from the pumps and discharging it outside the vessel, including also the means for controlling this discharge.
- B. The motors, which will be considered under the following further subdivisions: first, the motor proper, embracing the piston parts and cylinders and general manner of compounding the same; second, the adjustable gear for taking up the wear in the gearing, 45 and thereby keeping the piston parts in proper relation to each other; third, the roller-boxings for keeping the piston parts in proper relation to each other and to their cylinders; fourth, the adjustable stuffing-box, which when 50 used with the particular description of roller-boxing set out by me will prevent leakage of steam around the shafts; fifth, the self-adjusting motor-base, whereby the motors may be held down securely, yet will be free from 55 strains due to expansion and contraction.

C. The rotary pumps.

D. The general combination of all the mechanism to produce the desired result.

60 A. *The Jet Device.*

This, as has been previously pointed out, comprises, first, the feed mechanism, and, second, the discharge mechanism, which will now be described specifically.

- 65 1. *The feed mechanism.*—This is shown in

detail in Fig. 12 and embraces the pipes 1 and 1^a, which are designed to be disposed as shown in said figure, extending in inclined directions and united as shown, so as to form a junction in one pipe which is enlarged, as shown at 2, 70 and within which is the valve 3, so constructed as to reverse the course of the stream, so that the water as it is taken from the exterior of the vessel may pass directly to the pumps, or by reversing the valve the inlet from the exterior is shut off and communication established between the pumps and the interior of the vessel. The pipes 1 and 1^a terminate at their lower ends in the enlargements 1^b, which are attached to the bottom or bilge of the vessel inside the hull and are provided with the openings 1^c through the bottom, whereby water may be admitted from the outside. In each of these enlargements is a valve 4, having therethrough the passage 4^a, the valves 80 being designed to be turned, as seen in Fig. 12, so that the water may enter the openings 1^c and pass through the passages 4^a into the pipes 1 and 1^a and through the passage 3^a of the valve 3 into the pipe 5, and from thence 85 into a siphon 6, which extends some distance above the normal water-line of the vessel. 7 is a by-passage communicating with the siphon and with the enlargement of the pipe at 2. This by-passage 7 is closed when the valve 3 90 is turned, so that its passage 3^a is in communication with the pipes 1 and 1^a. When, however, the valve 3 is turned so as to close the passage from the pipes 1 and 1^a, the passage 3^a of said valve is brought into such position 95 as to open communication between the pipe 7 and the pipe 8, which extends from the opposite side of the enlargement 2, its lower end terminating in close proximity to the bottom of the hull of the vessel, as clearly seen in 100 Fig. 12, so that in case of leakage beyond the power of the vessel's pumps to control the pumps may be supplied with the water from the interior of the vessel, while admission of water from the outside through the openings 105 1^c is prevented, and thus the water may be pumped out and this without stopping the propulsion of the vessel. In Fig. 12 these feed-pipes are shown in the position they assume with relation to the hull X of the vessel, and in Fig. 1 they are shown in their relation to the other parts of the apparatus. In the latter figure I have illustrated two sets of these feed-pipes, (one set fore and the other aft;) but it is evident that in some cases one 110 of these sets may be omitted—as, for instance, in smaller vessels, where the requisite supply is not so great. These feed-pipes are so constructed that, as above stated, their siphons extend above the water-line, and at the top of each siphon is an outlet 7^a, as seen clearly in 115 Fig. 12, which opening communicates with the enlargement 7^b, in which is arranged an air-valve 9, having a passage 9^a, which valve may be moved so as to bring the passage 9^a in com- 120

munication with the opening 7^a and the air-pipe 9^b, whereupon the water will at once fall down to the water-line if the pumps are not then in operation. Ordinarily this valve will 5 be closed, as indicated in Fig. 12.

2. *The discharge mechanism.*—This is shown in detail in Figs. 2 to 8, inclusive, while in Fig. 1 it is represented in the position occupied with relation to the other parts of the apparatus.

Referring more particularly to Figs. 2 and 3, 10 and 10^a represent pipes which are inclined, as shown, and which instead of uniting to form a common discharge into the valve or 15 valve-chamber are arranged so that but one can communicate fully with the valve at the same time. This valve 11 has the passage 11^a therethrough and is mounted for movement within the enlargement of pipe 11^b. From the 20 upper extremity of this enlargement 11^b extend the pipes 12 and 12^a, which unite at their upper end and communicate with a siphon 13, which extends some distance above the normal water-line. At substantially the highest 25 point of the siphon is located an air-chamber 14^c, having its interior connected to the interior of the siphon through a small opening 14^d. The purpose of this air-chamber is to cushion the water in the siphon, so that when 30 the vessel is in a high sea the variation in pressure from a maximum to a minimum, due to the crests and hollows of waves over the discharge-openings, will not be transmitted at once to the pump, but will be cushioned at the 35 top of the siphon, thus relieving the pumps from the sudden shock or jar. This cushioning effect is particularly important in connection with a rotary pump of the construction shown by me and described hereinafter, since 40 such a pump has no valves to receive the strain, and as the water is driven out by the approach of two piston-wings toward each other a sudden increase in pressure of the exterior water on the discharge-openings would 45 act on the principle of the hydraulic press, and thus throw an enormous pressure on the piston-wings very suddenly and would tend to break them instead of merely slowing the speed of the rotary pistons, as will be the case 50 in my construction. At the upper portion or bend of the siphon in close proximity to the air-chamber there is an outlet 13^a, which 55 communicates with the pipe or enlargement 13^b, in which is located the valve 14, having the passage 14^a therethrough and which when the valve is properly turned affords a communication between the siphon (through the passage 13^a) and the air-pipe 14^b. This device forms an air-valve which serves to admit 60 air to the siphon in order to supply the air-chamber with air if for any reason it should be filled with water and also to break the siphon action when the pumps have stopped working. The lower end of this siphon is designed to be connected with the pumps. The

pipes 10 and 10^a are connected to the couplings or pipes or elbows 15, which extend from the casings or cylinders 16, one pipe connecting with one cylinder and the other with another. Within each of these cylinders is mounted 70 for rotation a valve 17, having extending diagonally therethrough a passage 17^a, which when the valve is turned in one position affords communication between one of the pipes 10 or 10^a and the outlet-opening 17^b in the bottom of the vessel, as indicated at the left of Fig. 3; but when the valve is turned in the opposite direction the outlet from the pipe 10^a is closed, as is also the opening 17^b, as indicated at the right of said Fig. 3. In Fig. 2 80 the parts are shown reversed, the valve 11 also being reversed, as will be readily understood. One set of these discharge-pipes is arranged upon each side of the keelson inside the hull and attached by means of the valve-casings to 85 the bottom of the vessel, the latter in this instance being shown with the inwardly-extending portions terminating in flanges 17^c, to which the flanges of the upper half of the cylinder-casings are bolted, the casings thus being made in halves for convenience of manufacture and in assembling the parts. The position of these discharge-pipes with relation to the inlet-pipes and the other elements comprising my propelling mechanism is clearly 90 illustrated in Fig. 1. The valves 17 are each carried by a shaft or stem 18, as seen clearly in Figs. 2 and 3, these shafts or stems passing into the cylindrical portions 18^a, as seen in Figs. 2, 3, and 7, within which they are secured, and extending through stuffing-boxes 18^b, beyond which they are mounted in suitable bearings or boxes 19, as shown. These valves, as well as the valves 11 and 14, are designed to be operated in any suitable manner. 100 The shafts 18 are shown as provided with gears 19^a for this purpose, while the shafts 11^c of the valves 11 are provided with gears 11^d, said shafts being mounted in suitable boxes or bearings 11^e, as shown most clearly in Fig. 110 6. The valves 4 are carried by shafts 4^b and provided with gears 4^c for a similar purpose. The valves 3 are carried by shafts 3^b and provided with gears 3^c, whereby they may also be actuated when desired. As the mechanism 115 for operating these valves forms no part of the present invention, an illustration thereof has not been given and seems to be unnecessary. In Fig. 8 I have shown how the valves 11 may be actuated by means of a lever 11^e, 120 attached to the shaft thereof.

B. *The Motor.*

This is considered under the following heads: first, the motor proper; second, the 125 adjustable gear; third, the roller-boxings; fourth, the adjustable stuffing-box; fifth, the self-adjusting motor-base.

1. *The motor proper.*—Each motor comprises a casing 20, Fig. 9, having two cylin- 130

drical overlapping compartments—one forming the ordinary steam-cylinder 23, while the other, 24, contains the rotary abutment 25, which is rotatable in its compartment upon a shaft 25^a and fits steam-tight therein, being provided with two recesses on opposite sides of the abutment to receive the wings or vanes 27^b of a rotary piston rotatably mounted in the steam-cylinder 23 and provided with a hub 27, mounted on a shaft 27^a. The motor-casing is formed in two parts for convenience of manufacture and assemblage, the heads or ends being designed to be detachably secured in place in any suitable manner, as by bolts. Steam is admitted at the bottom of the casing—as, for instance, through a pipe 21^a, entering the steam-cylinder, (through a pipe 28^c,) substantially in a line with the plane of junction of the two compartments 23 and 24. The steam expands against the rotary abutment 25 and against that piston vane or wing which is at that time uncovered by the abutment. By this expansion of the steam the piston is rotated in the direction of the arrow, Fig. 9, until the vane passes the opening of the exhaust-pipe, (indicated at 22^a,) after which it exhausts, the pipe 22^a being substantially opposite the steam-inlet. With the two vanes or wings on the piston a continuous rotation takes place, and of course the steam exhausts twice at each revolution of the piston.

As shown in the drawings, the rotary abutment 25 serves to protect one piston-wing at a time from the force of the steam, the piston-wings being received steam-tight in their respective recesses or vane-seats in the rotary abutment. The abutment-chamber, as shown, is of less diameter than the power-cylinder. The hub 27 of the piston and the rotary abutment 25 have their ends formed at right angles to their respective shafts, so that said ends may fit closely to the cylinder-heads and be made steam-tight.

It is to be understood that the inner diameter of the power-cylinder 23 is equal to the diametrical distance apart of the ends of the piston wings or vanes, which are intended to run in close contact with the interior of the power-cylinder, so as to prevent the escape of steam around the said vanes.

The outer ends of the wings 27^b are formed of parts separate from the piston, each part being provided with a rounded acting or outer face, as shown, and with projections or pins 43, which work in sockets or holes in the pistons. The said outer ends of the wings are, furthermore, provided with grooves 45, into which project flanges or lips 46, formed on the piston, as seen in Figs. 11^a, 11^b, whereby the said outer ends may have a limited amount of movement outward without permitting the escape of steam. At the lines of junction of the piston ends and the piston 47 are wedges adapted to be driven in from opposite ends of the piston, as seen best in Fig. 11^a, between

the outer face of the piston-body and the inner face of the outer ends of the piston-vanes, the said inner faces of the latter at these points being slightly tapered or inclined, as shown best in Fig. 11^a. It is of course necessary that these pins or wedges be driven in flush with or below the outer face of the piston, and to provide for their removal when desired I form the adjacent portions of the piston-body and vane ends with the depressions 48, as shown clearly in Figs. 11 and 11^a. 49 represents wedges or locking keys. They are inserted in openings in the outer faces of the piston, the outer ends of these openings 49^a being enlarged or countersunk, as shown in Figs. 11 and 11^a, for the same purpose as the depressions 48, just described. These locking devices 49 are designed to enter openings 50 in the projections or pins 43 of the piston-head, as seen best in Fig. 11^a.

To adjust the piston-head outward, the keys 49 are withdrawn and the wedges 47 driven in the required distance. Then the keys 49 are again inserted, and as they are driven in they engage the lower wall of the openings 50 in the projections 43, Fig. 11^a, drawing downward or inward on the same, thus locking the piston-head in its adjusted position. Normally the wedges 47 are not forced in to their full extent; but sufficient space is left, as seen in Fig. 11^a, so that the wedges may be driven in as the piston-head requires adjusting.

The shafts 25^a and 27^a, respectively, are suitably supported in roller-boxings and provided with adjustable stuffing-boxes and adjustable gears, as will be hereinafter more particularly referred to.

As seen in Figs. 9, 10, 11, 14, and 15, the casing or cylinder of the steam-motor is provided with a steam-jacket 28, into which live steam is admitted from a boiler 29 through pipes 30, which lead from said boiler and communicate with the jackets. In each of these pipes is a check-valve 30^a of well-known construction. 31 represents similar pipes connecting the steam-jacket with the boiler and provided with check-valves 31^a, all as best seen in Fig. 14. The live steam is admitted from the boiler through one of the pipes 30, as indicated by the arrow, and through the check-valve, and after entering the jacket it returns to the boiler through the pipe 31 and its check-valve, as indicated by the arrow, whereby upon any cooling or condensing of the steam in the jackets such steam would be immediately driven by the hotter steam from the boiler back into said boiler, in which manner the steam in the motor is maintained at boiler heat.

In use I propose to compound these motors. As a step in the explanation of my invention I have shown in Fig. 14 four of these motors disposed with their pistons upon one shaft 34, so that the power will be upon one shaft only, motion being transmitted to the other shaft 130

carrying the rotary abutments by means of the intermeshing gears 32 and 33, as clearly seen in Fig. 14, and in order to compensate for any wear that may take place upon these 5 gears which would destroy the proper relative positions of the abutments and pistons they are of novel construction, as will be hereinafter more particularly explained.

In Fig. 11 I have shown my proposed method 10 of compounding these rotary steam-motors for use in jet propulsion. In this view the motors are shown as disposed alternately throughout the compound, the first motor having the piston on one shaft and the second motor with 15 its piston on the opposite shaft, and so on throughout the compound. By this arrangement the power of the steam is equal on the two shafts, and still I retain the benefit of but two exhausts only in one motor to each revolution of the shaft or two revolutions of one 20 shaft to two exhausts in the compound motors. In this arrangement the pipes 30 and 31 are disposed upon alternately opposite sides; but this of course is not absolutely necessary. 25 The gear 32 and 33 employed in this arrangement of compound motors is the same as employed in the other form, a description of which will be given hereinafter.

In compounding the motors in my preferred 30 form I construct the casings of the individual motors so as to have spaces or chambers on the same side of the casing as are the rotary abutments, these spaces being indicated at 28^a 28^b in Figs. 9, 10, and 11. Fig. 9 represents 35 a section on the line 9 9 of Fig. 11, the piston, however, being shown in elevation. This view therefore shows the first individual motor of the compound or set. The steam enters through the pipe 21^a, passing into the lower space 28^b, 40 from whence it is conducted by a short pipe 28^c to the lower part of the steam-cylinder, expanding against the rotary abutment and rotating the piston in the direction of the arrow. Then it exhausts through the pipe 22^a, which is bent 45 downward, and to the right to deliver the steam into the upper space 28^a of the second individual motor of the compound. In this second motor the upper and lower spaces 28^a 28^b communicate through the openings 28^d. This 50 is best shown in Fig. 10, which is a view similar to Fig. 9, but taken on the line 10 10 of Fig. 11. The steam passes through the said opening 28^d into the lower space 28^b and thence across the steam-jacket 28 through the short 55 pipe 28^e into the steam-cylinder of said second motor, rotating the piston in the direction of the arrow, and exhausting through the pipe 22^b, which bends downward and to the left and delivers the steam into the upper space 28^a of 60 the third individual motor. In this motor the upper and lower spaces 28^a 28^b are also in communication with each other through openings 28^e, whereby the steam may pass from the upper space into the lower space, from whence 65 it passes through the corresponding short pipe

28^e into the steam-cylinder of said third motor, rotating the piston and escaping through the exhaust-pipe 22^c, which bends downward and to the right and delivers the steam into the upper space 28^a of the fourth motor. Here 70 the steam travels from the upper space 28^a to the lower space 28^b and then passes into the steam-cylinder of said fourth motor, finally escaping through the terminal exhaust-pipe 22^d to the air or to a condenser. (Not shown.) It 75 will be understood from this that only the first motor is supplied with steam directly from the boiler through pipe 21^a, while only the last motor has an exhaust-pipe 22^d, which allows the steam to pass to the atmosphere or to the 80 condenser.

In arranging my motor for jet propulsion I employ two sets—one in each side of the longitudinal central line of the vessel—and supply these two sets with steam from a common supply-pipe 21^b, leading from the boiler, as indicated in Fig. 1, the steam being taken from this common supply-pipe by branch pipes 21^a, as shown, a junction steam-valve 21^c being located at the common meeting-place of these 85 pipes. The specific construction of the junction steam-valve is obvious from Figs. 31 and 32. By means of this junction-valve the steam may be gradually cut off from one motor and turned on fully to the other motor, or it may be turned on partly to both motors or shut off entirely from both. This construction gives full control of the starting and stopping of the motors and also renders it possible, by a partial turning off of the steam from one motor 90 while allowing a nearly full head of steam to act on the other motor, to cause one motor to run slower and the other to run faster than the normal speed, thus causing less water to be forced out of one discharge-opening than 95 out of the other, whereby the vessel will tend to move in the arc of a circle whose radius depends entirely upon the relative difference in speed of the two motors. By this means 100 the vessel may readily be steered independent of any rudder mechanism and without checking the speed.

2. *The adjustable gear.*—Figs. 17 and 18 clearly illustrate this feature of the invention, and to these views particular attention is now 115 directed and from which it will be seen that the gear-wheel is composed of two parts or two gears arranged side by side upon the same shaft, the one wheel or section, 35, being keyed or otherwise made fast to the shaft, while the other section or wheel, 36, is loosely sleeved upon the same shaft, the key being shown at 37 in Figs. 14 and 18. The two sections when placed together constitute one 120 wheel. The loose wheel or section 36 is designed to be adjusted or moved to take up lost motion or wear by means of an eccentric lock, which is constructed as follows: Each 125 section is formed with a plurality of circular openings extending through the sections par- 130

allel to the central bore or passage for the shaft, the openings of one section being arranged to be brought in register with the corresponding openings in the other section. 5 In each opening in each section are inserted two semicylindrical parts, which together form a cylindrical plug 38, fitting snugly into its respective opening, the cylindrical plugs of one section being arranged to come opposite the corresponding cylindrical plugs of the other section of the gearing. Two plugs thus located opposite each other I will designate as a "pair" of plugs. Through each pair of plugs passes a pin-hole, which is arranged 10 eccentric to the geometrical axis of the plugs, the pin-holes each being conical, as shown in Fig. 18, in order to receive a tapered or conical pin 39, which may be driven tightly into the hole and is secured against withdrawal 15 by a cotter or wedge 39^a, passing transversely through its respective pin. As the pins 39 are driven into the holes in the pair of plugs they tend to force the two halves of each plug apart, thereby causing them to bind 20 tightly in their openings in the respective sections of the gearing. When it is desired to adjust the movable or loose section to compensate for wear, the cotters or wedges 39^a are removed and the pins 39 loosened, where- 25 upon the loose section may be turned in the proper direction. The plugs of each pair are then rotated in their respective openings in the sections to bring their eccentrically-located pin-holes in register again, whereupon the 30 pins are inserted into said pin-holes and driven up tightly to lock the sections in the adjusted position, the cotters or keys 39^a being then driven in place to hold the pins 39 against withdrawal. This adjustment may 35 be made at intervals whenever the gearing becomes worn, the effect of moving one section of the gearing with respect to the other being to take up the lost motion between one compound gear-wheel and the other. It will 40 readily be observed that by this form of device the gear can be kept perfectly adjusted and the piston-wings kept in perfect alinement relative to the wing-seats in the rotary abutments, so that all possibility of wear and 45 consequent leakage caused by them getting out of line relative to each other is avoided.

When placing two gear-wheels of the above construction on their shafts, they are so arranged that the sections keyed to the shafts 50 mesh with the respective adjustable sections of the opposite gear.

3. *The roller-boxings.*—As I pointed out in the introductory portion of this specification, my improvements in connection with the rotary motor relate more particularly to means 55 for preventing wear of the piston parts rather than to means for compensating for such wear after it has occurred. What I consider a principal part of the means for preventing such wear in the piston parts is the manner of

mounting the shafts which carry the piston and the rotary abutment, whereby the said shafts may be kept in alinement, so that the axis of revolution of the rotary parts may be maintained coincident with the geometrical axes of the cylinder and abutment-compartment. By this arrangement the piston and rotary abutment when properly fitted to their respective chambers may be maintained in proper relation to the same and not allowed 70 to scrape or drag on the interior walls of such chambers by the displacement of the shafts. These advantages are obtained principally by means of the roller-boxings, which will now be described specifically in connection with 75 Figs. 19, 20, 22, 23, and 25. In addition to the above advantages by means of the specific roller-boxings employed by me I am enabled to run the motor at a high rate of speed without undue heating of the bearings, as will be 80 explained hereinafter.

Referring to Figs. 19, 20, 22, 23, and 25, 85 52 is the boxing or housing, in the side walls of which are the passages for the main shaft and between which side walls are arranged 90 the rollers and the tail-block. 53 is the first roller-shaft. It is loosely supported in the side walls of the boxing, as seen best in Figs. 19 and 22, in horizontal line with the shaft 25^a, while 54 represents the first vertical roller- 95 shaft, likewise supported in the side walls of the boxing in vertical line with the main shaft, as seen in Fig. 22. On the shaft 53 are the rollers 53^a, more or less in number, as may be found most expedient. These rollers revolve 100 in contact with the main shaft, as indicated in Figs. 22 and 23, while upon the shaft 54 are the rollers 54^a, which also revolve in contact with the said main shaft, as seen clearly in Fig. 22. 55 is the second roller-shaft, 105 mounted in horizontal line with the shafts 25^a and 53, as seen clearly in Fig. 22, and upon this shaft are the rollers 55^a, the said rollers being so proportioned with relation to the size of the shafts that the rollers 53^a revolve in 110 contact with the shaft 25^a, and the rollers 55^a revolve in contact with the shaft 53, the rollers on the two shafts being so disposed that the rollers on the one shaft will be located 115 between the rollers on the other shaft. 56 is the second shaft in vertical alinement with the main shaft, and upon this shaft are the rollers 120 56^a, the disposition of the rollers on the vertically-aligned shafts being the same as that of those on the horizontally-aligned shafts, so that the rollers on the first shaft revolve in contact with the main shaft, and the rollers on the second shaft revolve in contact with the shaft of the first rollers, all as clearly shown. It is to be understood that none of the rollers 125 of the first roller-shafts 53 and 54 are to contact with their respective second roller-shafts 55 and 56. The latter shafts are therefore slightly reduced in diameter opposite the rollers of the respective first roller-shafts, as 130

shown in Fig. 19. The shafts of these rollers are geared together and to the main shaft, so that the said rollers will be positively revolved under all circumstances in harmony with the main shaft. In Fig. 19 I have shown these shafts as so geared. 57 designates the gear of the main shaft, which meshes with a gear 58 on the shaft 53, and on this latter shaft is another gear, 59, which meshes with 10 the gear 60 on the shaft 55, the gear 57 also being designed to impart motion to the two vertically-alined shafts 54 and 56 in like manner. This is shown also in Fig. 20.

The means for taking up the lost motion in 15 the second roller-shaft will now be described. As the means employed for the horizontally-alined shafts and for the vertically - alined shafts is the same, a description of the one is believed to be sufficient for a full and clear understanding of them all. Referring then to 20 Figs. 19 and 22, 61 designates the end plate or cap to the boxing, and 62 the tail-block. In the present instance I have shown eight screws as being employed in this connection; but it is 25 evident that this number may be varied, made more or less, as may be found most expedient, without materially affecting the result, and I therefore do not wish to be restricted to the number of screws employed. These screws 30 are in sets of four each, one set being so arranged as to have their nuts in the tail-block and the other four having their nuts in the cap to the boxing. The gearing is so arranged that four of these screws are made to turn simultaneously in one direction and the other four at the same time move simultaneously in the opposite direction. The four screws 35 63 are pivoted or swiveled in the tail-block 62, while their inner ends are threaded into the cap 61, as seen best in Figs. 19 and 22, and bear against the walls of the housing, while the other screws, 64, are swiveled or pivoted in the cap 61 and have their outer ends threaded into the tail-block. On the outer end of each 40 screw is a gear 65, Fig. 25, the three gears at the top meshing with each other and the three gears at the bottom meshing with each other. The intermediate gears on the horizontal shafts in horizontal line with the central gear 45 60 do not mesh with each other nor with the top and bottom gears, but instead mesh with the driving-gear 66, which is fast upon a stub-shaft rotatably mounted in the tail-block or fixed part of the housing, and this driving-gear 50 meshes with the central gears at the top and bottom and the two sides. This central or driving gear is somewhat wider than the other gears, as seen best in Fig. 22, so that it may be at all times in mesh with the other gears regardless 55 of the adjustment of the cap to the boxing, as will be readily understood. It will also be understood that the driving-gear 66 is revolvably mounted on its shaft and should be provided with some means whereby it can be turned to 60 adjust the screws. I have shown it in this in-

stance as provided with a knob or hand-wheel 67. The screws and gears for the vertical bearing or boxing, as above mentioned, are the same in construction and operation as those just described in connection with the horizontal bearing or boxing, and a further description thereof does not seem to be necessary. For convenience of operation, however, the shaft carrying the driving-gear is provided with a bevel-gear 68, which meshes with a bevel-gear 69 on a horizontal shaft 70, supported in suitable bearings and extended at one end, where it is provided with a suitable device, as a hand-wheel 71, by means of which the driving-gear and the screws may be operated. It is evident, however, that other means for this purpose may be employed, as may be found most convenient. The operation of this part of the invention will be apparent and its advantages will be readily appreciated. The weight of 85 the main shaft and the various lateral strains upon it are transmitted entirely to the rollers, and consequently there is no rubbing of the shaft. When it becomes necessary to take up the lost motion or to compensate for wear, 90 which, however, will be very seldom, all that is necessary to do is to turn the wheel 67 or the wheel 71, as the case may be, and as this is done motion is imparted to the driving-gear, which in turn imparts motion simultaneously 95 to all of the screws, and as the latter are turned the one set of four will revolve in one direction to move the cap, while the other set will revolve in the opposite direction, thus permitting the movement of the cap, the latter set 100 coöperating with the former set to hold the cap firmly in the newly - adjusted position. By this construction the caps may be readily adjusted from time to time to keep the shafts in proper alinement, thus preventing wear of 105 the piston parts or of the cylinder and abutment-chamber which would otherwise occur. Moreover, since the main shaft is carried on rollers and these again on other rollers the last roller-shafts, which are arranged to rotate 110 on stationary adjustable bearings, revolve at a much lower speed than does the main shaft, whereby the usual dangers of overheating the bearings are avoided.

4. *The adjustable stuffing-box.*—This comprises a special device which I am enabled to use for preventing the escape of steam around the shaft solely because of the adjustable roller-bearings employed by me. In other words, while my new stuffing-box will be particularly useful and efficient in connection with the mechanism for keeping the shafts in true alinement it could not be used without such mechanism, since it would be practically destroyed if used upon a shaft not kept in perfect alinement. This stuffing-box will now be described.

73 is the cylinder-head, which is provided with the annular flange 74, forming the inclosing portion of the stuffing-box.

75 is a thimble having a flange 75^a and a conical body portion provided with a bore to receive the shaft. This thimble is formed in two parts, as best seen in Fig. 21, and though it is preferred that it be in but two parts it is evident that a sectional thimble of more than two parts would be, in effect, practically the same. Hence I do not wish to restrict myself in this regard. The line of division between the two parts is on a center line with the opening, the thimble being sleeved upon the main shaft, as seen in Fig. 24. The flange 75^a of this thimble is of the same diameter as the interior diameter of the flange 74 of the stuffing-box, within which it is placed and fits tightly within the same, at the base thereof, as seen in Fig. 24. Around the conical part of this thimble, adjacent to its flange, are placed two rings 76 and 77, of such diameter as to fit neatly and tightly the inner walls of the chamber 74 and their surface or bores made to fit tightly the inclined or conical surface of the thimble. These rings are each divided into three or more segments, as seen in Fig. 21, and holes 78 are made through the joints of the ring 76 and a hole 79 in each of the segments of the ring 77 between the joints for the reception of their securing means, the object being that when in operative position the rings will break or rub joints, as will be readily understood. The openings 79 in the sections of the ring 77 are recessed or countersunk, as shown, to receive the nuts on the bolts now to be described. The under faces of the segments of the ring 76 are recessed to receive the collars on the bolts, as illustrated. In applying these rings there is a space left between the flange of the thimble and the inner ring, as indicated clearly in Fig. 24, to allow for adjustment in case of wear.

For the purpose of clamping the thimble 75 to the shaft 25^a its tapered or conical portion extends beyond the outer end of the flange 74 of the cylinder-head, as shown in Fig. 24, and a portion of this extended surface is screw-threaded, as seen at 80, which screw-threaded surface is designed to be engaged by the internal threaded portion 81 of the cap 82, having a corresponding conical portion, the internal threaded portion being formed upon the flange 83 of said cap, as shown, while the outer portion 84 of the cap is designed to approach to but not quite in contact with the outer end of the flange 74 of the cylinder-head, an annular chamber or cavity 85 being thus formed between the flange 83 and the outer wall 84, and in this annular chamber or groove are disposed the outer ends of the devices which are employed for securing the rings together and to the flange 75^a of the thimble 75. The thimble and the rings are secured together in this instance by means of screw-threaded rods or bolts 86, which pass loosely through the openings 79 in the ring 77, through the openings 78 at the joints of the sections of the

ring 76, and into the openings 75^b in the flange of the thimble 75. The openings 75^b are screw-threaded to receive the threaded bolts, while the openings in the rings are not threaded, but are larger in diameter than the bolts in order that the bolts may work loosely therein, as indicated clearly in Fig. 24. Fast upon each bolt is a collar 87, which collars work in the recesses or grooves 88 upon the under side of the ring 76, as shown in Fig. 24, these recesses being indicated by dotted lines in Fig. 21.

89 is a nut upon the bolt, which nut is seated in the countersink in the opening 79 in the ring 77, while 90 is another nut, also upon the bolt and working against the nut 89, as clearly seen in Fig. 24. The bolt is provided with a head or analogous device 86^a, by means of which it may be readily turned when desired to adjust the parts.

The operation will be readily understood. The parts are shown in position in Fig. 24, and should it become necessary to adjust the rings the cap 82, which is held to the shaft by a key 82^a, is removed by first withdrawing the key and then unscrewing the cap, when it may be moved upon the shaft a sufficient distance to uncover the bolts, which by wrench or suitable means can be adjusted to tighten the parts, the nut 89 being first turned and afterward the nut 90 to bind the parts in their adjusted position, whereupon the cap is again screwed on and the key 82^a inserted, thus firmly securing the parts in their adjusted position and producing an absolutely steam-tight joint in which there is practically no wear so long as the shaft is not thrown out of alinement, as it will not be with the roller-bearings provided by me if said bearings are kept properly adjusted.

5. *The self-adjusting motor-base.*—Notwithstanding the various means provided by me for preventing wear in the motor proper, such wear would take place to a serious extent at high speeds, owing to the unequal expansion and contraction of the various parts, which would occur were it not for the self-adjusting motor-base, which forms one of the essential features of my invention and which prevents the said unequal expansion and contraction. This feature of my invention will now be described, reference being made to Figs. 26 to 30, inclusive, and also to Figs. 15 and 23.

In Fig. 15 it will be seen that the subbase 20^a of the motor is made hollow, the interior of said subbase being in communication through an opening 20^b with the interior of steam-jacket 28, which surrounds the motor. The subbase rests upon a motor-base which comprises two longitudinal stringers 93, connected by transverse girders 93^a 93^b 93^c, these parts all being hollow and in communication with each other, as shown in Figs. 26 and 27. Furthermore, the central transverse girder 93^a is provided with openings 93^d, which communicate with the interior of the motor-subbase 20^a.

At each end of the stringers 93 are hollow tie-plates 94, which are in communication with the interior of the said stringers 93 through openings 94^a, these tie-plates 94 carrying the 5 housings 52 of the roller-boxings, the housings of each boxing having a hollow flanged portion 52^a, which is secured to the respective hollow tie-plate 94, the interiors of the said hollow flanged portions and the tie-plates being 10 in communication through the openings shown at 94^b. The lower surface of the tie-plates 94 are each provided with downward-extending ribs 94^c, which enter grooves in the upper surfaces of the stringers 93, as will be 15 seen in Fig. 23.

Steam is admitted to the hollow portions of the motor-base from the steam-jacket of the motor attached and secured thereto, as seen in dotted lines in Fig. 15, the object being to 20 provide for equal expansion of all parts of the steam-motor, its motor-base, and the roller-boxings, thus preventing cramping and friction, as well as breakage, of parts in the steam-motor and base, the advantages of which will 25 be apparent to any one familiar with this class of machinery.

95 is a bed-plate, upon which are supported the pillars or piers 96, which are bolted to said bed-plate, as seen in Fig. 27, and upon 30 the upper ends of which the stringers 93 rest, but which are not secured directly thereto.

97 is a plate extending lengthwise of the motor-base, upon the under side thereof, and secured firmly thereto in any suitable manner, as by bolts, as seen in Fig. 29. This plate has depending therefrom centrally the male portion 98 of a coupling, which is provided with the opening 99, which, as seen most clearly in Fig. 28, is struck from one center, the 35 upper half of said opening being a semicircle of greater diameter than the lower half for a purpose which will soon become apparent.

100 is a female portion of the coupling formed in two parts, the lower part of which 45 has the semicircular opening 101 upon its upper face, while the upper part 102 has the semicircular opening 103 in its lower face, the two sections being designed to be bolted together, as indicated clearly in Figs. 27 and 50 30, and when the sections are thus secured the opening formed by the semicircular openings 101 and 103 will be the reverse of the opening 99 in the male portion—that is, the upper half of the opening will be of less diameter than that of the lower half of the opening. Some suitable means should be provided for introducing a lubricant, and in Fig. 30 I have shown one form of means for this purpose; but it is evident that the oil may be introduced in any other manner both to this and 60 to the male portion, if desired. The plate 97 also carries near each end the depending portions 104, which, however, are disposed at right angles to the portion 98, and these portions 104 form part of the couplings at the

ends, which are constructed in the same manner as that just described, 105 designating the lower half of the female portion, which is secured to the bed-plate, and 106 the upper portion which is secured thereto, it being understood that the male and female portions of the coupling are provided with openings of the same character as those illustrated and described in connection with the central coupling. 75

It being understood that the lower portions of the couplings are fast to the bed-plate and the plate 97, carrying the male portions of the couplings, is fast to the under side of the motor-base 93 it will be readily seen that when the bolts are placed in position, so as to unite the male and female portions of the couplings, the motor-base is firmly drawn down into position and secured to the bed-plate. The bolts 107 employed for this purpose are 80 strong, so as to withstand all the strain to which they may be subjected, and when placed in position they will have a bearing upon the walls of the lower half of the openings in the male portions and will be out of contact with the walls of the upper half of said openings, while they are in contact with the walls of the upper half of the openings in the female portion and out of contact with the walls of the lower half of said openings. It will thus be seen 85 that while serving to securely hold the parts against undue movement the parts are free to expand and contract under varying conditions of the metals without injury to any of the parts. The disposition of the bolts at right 90 angles to each other in the end and central couplings serves to securely hold the parts of the motor-base against lateral as well as longitudinal movement, yet permits of the necessary movement, due to expansion and contraction of metals in the steam-motor and its base from heat and cold, not only lengthwise, but 95 transversely of the motor-base. This adjustment is automatic, or, in other words, the motor-base is self-adjusting to compensate for the 100 cooling or heating of the metal in the steam-motor and its base and roller-boxings, whereby cramping and breaking of the parts is entirely overcome, the shafts are maintained in alignment, and the wear of the piston parts from 105 this cause is avoided.

The making of the self-adjusting motor-base hollow for the introduction of steam is an absolute and indispensable necessity in order to provide for equal expansion of metal in the motor-base in harmony with the expansion of metal in the steam-motor secured to the same. 110

C. The Rotary Pumps.

As I have heretofore explained in the introductory part of this specification, the most satisfactory rotary pump of which I have any knowledge is that type of pump in which two rotary pistons intermesh with each other, each piston being mounted on a separate shaft. I 125 130

employ this form of construction, which is old and well known; but to adapt it to my use I introduce a few specific changes, which will be pointed out. A cross-section of a rotary pump of this kind is shown in Fig. 13, wherein 5 25^a 27^a are two rotatable shafts, upon which are fixed the rotating pistons 41, each having a series of vanes or wings with vane-seats between them, the ends of the vanes of each piston 10 ton being arranged to enter and fit water-tight in the vane-seats of the other piston. The outer end 42 of each piston-vane is provided with means for taking up the wear, comprising a construction similar in all respects to 15 that described hereinbefore in connection with the motor and shown in detail in Figs. 11^a and 11^b. Hence no further description of such means for compensating for the wear on the pistons and on the interior of the cylinders 20 will be necessary. The said pistons 41 rotate in cylinders which overlap each other and which are formed in the casing 40, said casing being made in two parts, as shown, for the purpose of ease in manufacture and assemblage 25 of the parts and repairs. The inlet 22 for the water is at the top of each casing over the plane of junction of the two cylinders, while the outlet 21 is directly below the inlet, as will be clear from Fig. 13. 30 The pumps described are connected in sets, four pairs of pistons being shown in one set, occupying one compound casing in Fig. 16, the two shafts which carry the pistons being geared together by the gear-wheels indicated 35 at 32 and 33 in said Fig. 16.

In order to strengthen the piston-hubs and also to support or brace the piston wings or vanes, I provide each piston with a collar at one end, each collar being formed integral 40 with its corresponding piston. These pistons are so arranged in their casings that the collar of one will be at the ends opposite the collar of the adjacent piston of the same pair—that is to say, in a series of pairs forming a 45 set of pumps, such as shown in Fig. 16, the collars 41^a of the pistons on the right hand will be faced toward one end of the machine, while those on the pistons at the left will be faced toward the other end of the machine. 50 The partitions 41^b between the various pairs of pistons are provided with circular recesses, into which the respective collars enter and fit snugly. The ends 41^c of the casing are each provided with a similar recess to receive the 55 collars on the outer pistons. Moreover, the diameter of the collars 41^a are less than the distance apart of the shafts 25^a 27^a, whereby it follows that the two recesses for the pistons in a partition will not run into each other, as 60 will be understood from Fig. 16, whereby leakage through the adjacent recesses will be avoided.

The inlets 22 of the various pumps of a set are supplied with water from a common pipe 65 108, as shown in Fig. 1, a branch inlet-pipe

being provided for each pump, while the discharge-pipes 21 from all the pumps of a set are united to a common discharge-pipe 110, as will also be seen in said Fig. 1. The individual discharge-pipes of each pump are 70 not circular in cross-section, as is usual, but are substantially rectangular, being of a width equal to the width of the pistons, thereby permitting a ready escape of the water from the pump to the main or common discharge-pipe 110. A cross-section of one of the discharge-pipes is shown at the bottom of Fig. 13. 75

The general operation of the form of rotary pump employed by me is old and well known and need not be described herein. 80 However, there are some specific features of the operation which arise through the combination of this form of pump with the form of motor, roller-bearing, &c., employed by me, which will be referred to hereinafter. 85

D. The General Combination.

Having now described the various parts of the mechanism which I employ in my invention for the propulsion of vessels, it remains 90 only to set forth the manner in which they are combined and operate to the accomplishment of the desired result.

The parts are shown assembled in Fig. 1. The supply-pipes fore and aft are connected 95 in the manner illustrated, the siphons 6 being connected with the pipes 108, which by their branches 109 communicate with the inlets of the pumps, while each pump outlet or discharge is connected by means of a pipe 110 100 with the siphons 13 of the discharge-valves, and the other parts being connected up, as illustrated and as has been heretofore described, the operation is as follows: One of the discharge-pipes on each side of the keelson 105 being directed aft and the other one forward and it being desired to propel the vessel forward the aft discharge-pipe valves are opened and the forward ones closed and then the discharge junction-valve 11 turned so as to direct the water aft and the vessel is propelled 110 forward. By reversing the valves the motion of the vessel is reversed. By turning the current of the stream on one side of the keelson forward and that on the opposite side aft 115 the vessel may be turned around end for end, and it is obvious that the vessel may be steered in the same manner, the action of the water in opposite directions serving the same function as a rudder, but being more positive and insuring the steering of the vessel with greater 120 power, certainty, and accuracy.

In case of leakage the whole power of the motors may be turned to pumping the water out of the hull and at the same time to propelling the vessel, as though the pumps were supplied with water from the outside, this change being produced without stopping the motors in the following manner: The valve 3 125 is turned so as to shut off the admission of 130

water from the outside of the hull, thus throwing its passage-way 3^a into communication with the pipe 3, so that the water may be taken from the interior of the vessel and from 5 the bottom thereof, as will be readily understood upon reference to Fig. 12.

In case of fire the vessel may be flooded with water from the discharge-pipes, and if the vessel is at its dock or not in motion by turning 10 the discharge junction-valves 3 so as to direct the currents of water equally forward and aft the vessel may be so overflowed with water as to extinguish the flames and still not move from its moorings. Moreover, the 15 pumps may be used to pump the water (which has been thrown into the vessel to extinguish the fire) outward through the discharge-pipes to propel the vessel, if necessary.

When it is desired to reverse the direction 20 of motion of the vessel, a special manipulation of the valves is necessary in order to avoid undue shocks or concussions. For example, while the vessel is being propelled forward the forward discharge-valves are shut and the 25 aft ones open, the junction-valves 11 being turned so as to supply water from the pumps to the said rear discharge-valves. Now when it is desired to reverse the apparatus, so as to 30 propel the vessel rearward, the forward discharge-valves are opened, thus letting the outer water rush in and fill the forward discharge-pipes as far as the junction-valves. The latter are now gradually turned, whereby the direction of discharge is changed, so 35 that instead of passing out of the aft discharge-openings alone it passes partly out of the aft ones and partly out of the forward ones. The further rotation of the said junction-valves causes the water to be discharged entirely 40 through the forward discharge-openings. This being accomplished, the aft discharge-valves may then be closed. The vessel will now be propelled rearward. In this manner the direction of the vessel may be changed 45 without stopping the motors and without shocks or concussions. A reverse operation of the various valves takes place when the vessel is to be again propelled forward.

By this construction of jet-propulsion apparatus 50 vessels may be run in either direction and steered without separate steering-gear, thus rendering it possible in case any accidents occur to the usual steering-gear to maneuver a vessel provided with my apparatus 55 even better than it can be done by the said steering-gear above.

It will be observed that by the mechanism hereinbefore described the bilge-water can be pumped out of the vessel as often as may be 60 needed without cost, if the vessel is in motion, and, if necessary, fresh water may be admitted, so as to wash the interior of the vessel and then the same pumped out in the manner just described. By this means I am enabled to 65 keep the lowermost part of the vessel as clean

and healthy as the upper deck, and one of the greatest evils of ocean travel will thus be entirely eliminated. The result will be prevention of diseases, such as yellow fever and the spread of the same, thus rendering the ship's 70 hold comfortable and healthy.

The motors and pumps will serve effectually as air-pumps, so that by shutting off the inlet of water and connecting these pumps with the air I can force fresh air through all parts of 75 the vessel, and thus keep the temperature of the same at any desired degree, while keeping the air pure. It is also evident that when the vessel is not in motion these pumps may be employed, if desired, to fill receivers with 80 compressed air, to be used as occasion may require.

It will be observed that the two sets of pumps are independent of each other and capable of 85 independent operation, so that should it become necessary one set may be employed for pumping the water and the other set used for pumping and compressing air. In fact, the two sets of devices connected up, as seen in Fig. 1, are capable of independent operation 90 whenever occasion may require.

By referring to Figs. 2 and 3 it will be observed that the discharge-pipes are disposed at an angle to the perpendicular, which angle may be varied as experience demonstrates is 95 the most desirable. It will also be observed that the outer peripheries of the valves are disposed within the outer surface of the hull, and in order to avoid any sharp angles for contact with the water the outer plates are 100 tapered, as seen most clearly in Figs. 2 and 3. In Fig. 7 this disposition of the valves within the limits of the outer walls is clearly illustrated, and this construction provides against the contact of the valves with any 105 substances or articles that might be in the path of the vessel. The inlet-valves are similarly arranged. Moreover, since the discharge-pipes have their openings at the bottom of the vessel the exterior pressure of the 110 water against which the discharging-jets must act is a maximum, and consequently the reaction due to the force of the jets is also a maximum, which would not be the case if the discharge-openings were higher up, and therefore 115 nearer the water-line. In addition it is to be noted that the water is projected outward from the bottom of the vessel in such a manner that the axis of the jet will lie in a vertical plane (assuming that the vessel is 120 in its normal position) parallel to the vertical plane through the longitudinal center of the vessel, and will strike the water exterior to the vessel at an angle to the normal water-level. By this arrangement the water forming the jet 125 will be driven down into deeper water than that at the mouth of the discharge-opening, thus encountering a continuously-increasing pressure of water, and thereby, for this reason, giving a maximum reaction of the jet to 130

propel the vessel. Hence it becomes possible for me to project the water forming the jet at a higher velocity than would otherwise be advisable, and consequently the diameter 5 of the jet may be smaller, thus rendering it possible to use smaller pipes and smaller pumps than would be the case if the jet of water were projected horizontally and nearer the water-line. Thus for the same amount of 10 propelling power a smaller weight of machinery can be used.

Attention is particularly invited to the fact 15 that the siphons 13 13 extend above the normal water-line of the vessel. By this construction a maximum head of water is maintained on the pumps when running, so that in heavy seas, which vary the pressure on the discharge-openings, the effect of such variation and rapid alteration of pressure of the 20 exterior water will not cause such a sudden variation in the load on the pumps, and hence the motors will not alternately race and then stop, as they would if the siphons in the discharge-pipes were omitted; and since the 25 jets discharge downward into the water, as has been explained above, the difference between the maximum load and the minimum load is much smaller in comparison to the normal load on the pumps and motors than if 30 the discharge-openings were nearer the water-line of the vessel and arranged to project the jets horizontally. Thus there will, for this reason, be less variation in speed of the vessel or of the pumps and motors. Furthermore, 35 when the mechanism is not in operation the air-valves 9 14 at the tops of the siphons may be opened to allow the water in the apparatus to drop to the level of the water outside, thereby keeping the pressure of the 40 exterior water off the pumps.

As I have previously pointed out, I employ 45 rotary pumps in order not to have reciprocating parts which will cause vibration and undue wear and which prevent the operation of the apparatus at very high speeds. Moreover, as the most efficient form of rotary pump known at present is the one shown by me having two rotating pistons and two shafts, the pressure or resistance thereby being the same on each shaft, I therefore employ 50 such a pump and combine with it my compound motor, which also has two shafts, the motors being so compounded that the shafts are driven by an equal number of pistons 55 on each. By this combination the power transmitted to each motor-shaft is the same, and these motor-shafts are coupled direct to the pump-shafts, thus transmitting an equal power to each pump-piston directly. As the work to 60 be done by the two pistons of each pump is the same, I obtain an equalization in the application of the power which avoids all that straining and tension which would come through an attempt to drive the pump with 65 one shaft. Also I avoid the wear which would

occur if intermediate gearing were introduced between a single power-shaft and a rotary pump having two pistons. Consequently by my construction, while I use gearing between the two shafts of the pump and also of the 70 motor, this gearing is not intended, essentially, for the transmission of power from one shaft to the other, but serves merely to keep the two shafts in their relative positions, so that the pump-pistons will move synchronously, 75 thus keeping the said rotary parts in their proper relative positions, so that there can be no leakage of water or steam, wear, or breakage due to one piston rotating out of unison with its corresponding opposite rotating part, 80 the outer ends of the wings or vanes of each piston thereby always coming truly into their respective vane or wing seats.

Since the two shafts of the motors and pumps would tend to spread away from each 85 other, owing to the particular construction of motors employed by me, I provide the special roller-bearings, which I have described, in which the shafts are held firmly against spreading by rollers acting in opposition to the force 90 which tends to spread them. Moreover, since these roller-bearings reduce the speed of the shafts before transmitting the weight of said shafts to the stationary portions of the bearings the motors and pumps may be run at a 95 high rate of speed without unduly heating the bearings. Besides, these roller-bearings do away with the complicated means for taking up wear in the piston parts, since they may be adjusted to maintain the shafts in alinement, 100 thereby preventing wear of the piston parts and of the interior of the cylinder. At the same time by the use of these roller-bearings I am enabled to employ my improved adjustable stuffing-boxes around the shafts on 105 the motors, thus avoiding the use of packing as now employed in the common stuffing-box, which would require considerable pressure to keep it packed and cause more of a loss from friction than in the form used by me. 110

To keep the shafts in their proper alinement would be extremely difficult or practically impossible were the roller-bearings mounted in the usual way on a bed-plate, since the motors when first started would be cooler than after 115 they had been running for some time, and hence there would be an expansion in the motor parts due to the increase in temperature, which would cause the shafts to be separated farther at the motor proper than at the roller-bearings, thus throwing said shafts out of line. This would cause such a great wear of the piston parts at the high speed at which it is necessary to run the motors for jet propulsion that the objects to be attained by my 120 roller-bearings would be defeated. Hence to overcome this objection I cause all parts of the motor-base to be uniformly heated by the introduction of steam into the motor-base, the latter being coupled to the bed-plate by a 125 130

special construction in order to allow it to expand and contract, and yet be held down rigidly to the said bed-plate.

In the description of my jet propulsion apparatus I have referred especially to that form of my improved compound motor in which the pistons and rotary abutments are alternated throughout the compound or set. This is necessary on account of using the compound motor for operating a rotary pump with two shafts, as has been heretofore explained. In Fig. 14, however, I have illustrated one form of compound motor in which the pistons are all on one shaft. In this construction the power is all on one shaft, and this form of motor I propose to employ in connection with my jet propulsion apparatus to drive a screw-propeller.

The jet propulsion apparatus may be used either alone or as auxiliary to a single screw. It has long been well known that the use of twin screws for propelling a vessel was advantageous over a single screw aside from the mere question of difference in speed, since with twin screws one might be run faster than the other and the vessel thereby turned on a long arc or one screw could be run in a direction opposite to the other, whereby the vessel could be turned on a short arc. By employing my jet propulsion apparatus in such vessels as are already provided with a single screw all the advantages of the twin screw may be obtained with less cost, less weight, and less bulk than by replacing the single screw and its engines by twin screws and engines therefor. Hence my jet propulsion apparatus has a special function even as a mere auxiliary to a single screw, rendering it possible to turn the vessel either on a long arc or a short one by a proper manipulation of the jet propulsion apparatus, as will be fully understood from the description hereinbefore given. Furthermore, referring to the roller-boxings, (shown in Figs. 19, 20, 22, 23, and 25,) instead of using screws all threaded in the same manner and gearing for rotating one set in a direction reverse to the other I may also employ one set of right-hand screws and one set of left-hand screws, with gear-wheels on the outer ends, which are all in mesh with each other, so as to rotate in one direction. This will produce the same result as the construction hereinbefore shown and described.

The roller-boxing herein shown and described is not claimed herein, as the same forms the basis of the patent, No. 667,810, granted to me February 5, 1901. Neither do I make any claim in this application to the adjustable stuffing-box herein shown and described, as that forms the subject-matter of an application filed by me August 28, 1901, Serial No. 73,631. The self-adjusting motor-base, the adjustable gear, the adjustable piston-wings, and the other features not herein

claimed are claimed in my application filed March 20, 1902, Serial No. 99,122.

Having thus fully described my invention, what I claim as new, and desire to secure by Letters Patent, is—

1. In a jet propulsion apparatus for vessels, the combination with a rotary pump and means for operating the pump, of a jet mechanism having a discharge-pipe connected to the pump and provided with a siphon which extends considerably above the normal water-line of the vessel, substantially as described. 70

2. In a jet propulsion apparatus for vessels, the combination with a rotary pump and means for operating the pump, of a jet mechanism having a discharge-pipe connected to the pump and provided with a siphon which extends considerably above the normal water-line of the vessel, and an air-chamber in communication with the siphon, substantially as described. 80

3. In a jet propulsion apparatus for vessels, the combination with a high-speed rotary pump and means for operating the pump, of a jet mechanism having discharge-pipes connected to the pump and provided with siphons which extend considerably above the normal water-line of the vessel, substantially as described. 85

4. In a jet propulsion apparatus for vessels, the combination with a pump and means for operating the pump, of a jet mechanism having a siphon extended above the normal water-line of the vessel and discharge-pipes connected to the pump and opening through the bottom of the vessel at each side of the longitudinal center of said vessel. 95

5. In a jet propulsion apparatus for vessels, the combination with a pump and means for operating the pump, of a discharge-pipe provided with a siphon and connected to the pump and opening at the bottom of the vessel, substantially as described. 105

6. In a jet propulsion apparatus for vessels, the combination with a pump and means for operating the pump, of a discharge-pipe a siphon extended above the normal water-line of the vessel and connected to the pump, opening through the vessel, and arranged to discharge at an angle downward. 110

7. In a jet propulsion apparatus for vessels, the combination with a pump and means for operating the pump, of a discharge-pipe provided with a siphon and connected to the pump, said discharge-pipe having its axis lying in a vertical plane parallel to the vertical plane through the keel of the vessel and arranged to discharge downward through the bottom of the vessel at an angle to the normal water-line, substantially as described. 115

8. In a jet propulsion apparatus, the combination with two pairs of discharge-pipes having siphons extended above the normal water-line of the vessel and arranged, one pair on each side of the longitudinal center of the ves- 125
